(57) **CLAIM**

We claim the ornamental design for a sleeve for holding an aerosol generator, as shown and described.

DESCRIPTION

FIG. 1 is a rear perspective view of a sleeve for holding an aerosol generator.

FIG. 2 is a front view of the sleeve for holding an aerosol generator depicted in FIG. 1.

FIG. 3 is a rear view of the sleeve for holding an aerosol generator depicted in FIG. 1.

FIG. 4 is a top view of the sleeve for holding an aerosol generator depicted in FIG. 1; and,

FIG. 5 is a right side view of the sleeve for holding an aerosol generator depicted in FIG. 1.

The broken lines in the drawings depict portions of the sleeve for holding an aerosol generator that form no part of the claimed design.

1 Claim, 5 Drawing Sheets
